TELESCOPING WAND FOR A VACUUM CLEANER

James Anderson, 48 Lombardy Road, Baie d Durfe,
Quebec, Canada

Filed Feb. 14, 1969, Ser. No. 15,780

Term of patent 14 years

Int. Cl. D15—07

U.S. Cl. D49—17

FIG. 1 is a perspective view of a telescoping wand for a vacuum cleaner according to my new design.

FIG. 2 is a partial perspective view illustrating the appearance of the bottom surface of the wand shown in FIG. 1.

FIG. 3 is an end view looking at the left end of the wand as shown in FIG. 1.

FIG. 4 is an end view thereof looking at the right end as shown in FIG. 1.

I claim:

The ornamental design of a telescoping wand for a vacuum cleaner, as shown and described.
